COMBINED TOOTHBRUSH HOLDER AND TOOTHPASTE DISPENSER

Wayne Paul Hilgendorff and Sue J. Hilgendorff, both of 7061 S. 17th East St. 84121, and Norman Alexander
Hilgendorff, 450 E. Robert Ave. 84115, all of Salt
Lake City, Utah

Filed Dec. 20, 1971, Ser. No. 210,290

Term of patent 14 years

Int. Cl. D6—06

U.S. Cl. D6—91

Fig. 1

Fig. 3

FIG. 1 is a front perspective view of a combined toothbrush holder and toothpaste dispenser showing our new design;

FIG. 2 is a side elevational view thereof; and

FIG. 3 is a top plan view thereof, showing the doors in an open position.

We claim:

The ornamental design for a combined toothbrush holder and toothpaste dispenser, as shown.
